UNITED STATES PATENT OFFICE

EDGAR WILTON SMITH, OF EDINBURGH, SCOTLAND, AND THOMAS EWART PHYTHIAN, OF LEEDS, ENGLAND, ASSIGNORS TO R. W. CRABTREE & SONS, LIMITED, OF LEEDS, ENGLAND

INKING MECHANISM FOR PRINTING MACHINES

Application filed May 8, 1930, Serial No. 450,743, and in Great Britain March 6, 1929.

This invention relates to inking mechanism for printing machines, and especially to that type of inking mechanism in which ink is by capillary attraction taken up by a rapidly rotating roller from the fountain roller, for its distribution and application to the printing cylinder or printing surface.

The invention comprises means whereby a continuous and infinitely variable movement derived from the press mechanism is imparted to the fountain roller independently of the speed of the press.

According to the invention, moreover, the driven part, that is to say, the fountain roller, may be rotated through ratchet mechanism or its equivalent by means of a double pawl device or its equivalent having a variable stroke whereby an effective movement is imparted by each stroke of the pawl carrier or its equivalent, and thus a substantially continuous movement transmitted to the driven part, means being provided whereby the extent of movement thereby transmitted to the driven part is infinitely variable at will.

According to the invention, moreover, the movement is imparted to the fountain roller through two cam levers so operated that one is always on the forward stroke before the other has completed its full stroke, so that thus the movement imparted to the fountain roller is substantially continuous at any speed.

The invention comprises the constructional features hereinafter described.

The invention is illustrated, by way of example, in the accompanying diagrammatic drawings.

Figure 1 is a side elevation of one construction of inking mechanism according to the invention.

Figure 2 is an end elevation corresponding to Figure 1, showing the mechanism at one end of the fountain roller.

Figures 3 and 4 are respectively views similar to Figures 1 and 2 of a modified construction.

In carrying the invention into effect according to the construction represented in Figures 1 and 2 of the accompanying drawings, the ink fountain α is raised from the

position that is usual, and a small ink drum b is mounted above and in proximity with the fountain roller c and their relative positions so determined that there is no contact, and that in the rapid rotation of the ink drum b a film of ink may be taken up from the fountain roller c by capillary attraction, and the ink thence distributed and applied to the printing cylinder. It will thus be understood that the usual so-called lifting roller and the mechanism for its actuation are dispensed with.

Movement is imparted to the fountain roller c through gear wheels d, e from a pawl and ratchet or similar mechanism. Thus the outwardly protruding end of the spindle of the fountain roller c may have mounted upon it at one end inside the frame of the press a gear wheel e in engagement with another gear wheel d disposed upon a parallel disposed spindle f upon which also two ratchet wheels g, h are mounted in juxtaposition. Two pawl carrying arms g^1, h^1 are freely mounted upon the same spindle, one arm g^1 at the inner side of the innermost ratchet wheel g , and the other h^1 on the outer side of the outermost ratchet wheel h . A pair of links g^2, h^2 is connected at one end to the outer end of the respective arms g^1, h^1 , and the opposite end of each link is connected to the lower end of a corresponding slotted pivoting arm g^3, h^3 . The respective slotted pivoting arms g^3, h^3 depend from the respective ends of a horizontally disposed spindle i carried centrally within a sliding block i^1 adapted to be adjusted vertically within a central slot j^1 in a bracket j mounted upon a support secured to the side of the ink fountain, or to the press frame; it being understood that the bracket j is centrally disposed between the two respective depending slotted arms g^3, h^3 .

Two cam levers k, l are mounted upon a transversely disposed spindle m set below the bracket j , the cam levers being disposed beneath, and at each side of the centre line of, the bracket j . One arm of the respective cam levers k, l is upstanding while the other extends forwardly at about a right angle (or at an angle slightly more or less) to the other,

and the forwardly extending arms are juxtaposed and each carries a roller k^1, l^1 in a position to engage a corresponding cam k^2, l^2 (not shown in Figure 1) which cams are mounted upon the same transversely disposed spindle n , at right angles to a shaft o mounted beside the press frame and deriving movement from the press mechanism, the movement being imparted from the shaft through a pair of bevel gear wheels o^1, o^2 .

It will be observed that for the sake of clearness, one only of each of the pairs of levers k, l links g^2, h^2 , and arms g^1, h^1, g^3, h^3 are shown in Figure 1 of the drawings.

At the upper end of each of the upstanding arms of the cam levers connection is made, by means of a pin k^3, l^3 engaging in the slot g^4, h^4 with the respective slotted pivoted arms g^3, h^3 , the lower ends of which are connected to the respective pawl carrying arms g^1, h^1 by the respective links g^2, h^2 as hereinbefore described.

It will be understood that the sliding block i^1 may have movement imparted to it vertically upward or downward in the slot j^1 provided in the bracket j , as, for example, by means of a screw-threaded spindle i^2 passing centrally through the block, the end of the spindle passing through the upper end of the bracket j and being mounted therein so as to be axially immovable and carrying an operating wheel or handle i^3 at its upper end for the rotation of the spindle.

The cams k^2, l^2 are set in substantially diametrically opposite positions in juxtaposition upon the spindle n whereby they operate alternately to impart movement to the respective pawl carrying arms g^1, h^1 , and the teeth of the ratchet wheels g, h and the pawls are so arranged as to impart movement to the fountain roller c in the same direction, whereby the movement of the fountain roller is substantially continuous, the cams k^2, l^2 being so arranged that one of the two cam levers k, l has begun the forward stroke before the other has completed its full forward stroke. The cams are advantageously so formed as to give a long lift and a quick fall to the rollers k^1, l^1 : and these movements are imparted to the cam levers k, l which in turn impart movement to the slotted arms g^3, h^3 and to the links g^2, h^2 , and thus through pawl carrying arms g^1, h^1 to the ratchet wheels g, h which rotate the spindle f and thus, through the gear wheels d, e , of the fountain roller.

It will be understood that since by manipulation of the wheel i^3 it is possible to adjust the sliding block i^1 upwardly and downwardly in the slot i^2 , it is also possible to adjust the position of the slotted arms g^3, h^3 and their pivot spindle i in relation to the pins k^3, l^3 which remain always at a fixed radius from the spindle m . Thus, according as the pins k^3, l^3 are disposed towards the upper or

lower ends of the slots g^4, h^4 in the arms g^3, h^3 by adjustment of position of the latter, so the angle of oscillation of the said arms is increased or reduced. Consequently, the angular movement of the pawl-carrying arms g^1, h^1 is also increased or reduced with a resultant control of the travel of the ratchet wheels g, h .

It will be understood that gears may connect the spindle f to the fountain roller inside the frame at both sides of the machine; and that the fountain roller may be divided in the middle to allow either side to be disconnected at will.

It will be further understood that instead of duplicating the operating mechanism in the manner hereinbefore described the pawl carrying arms may be set in opposite juxtaposed positions and the respective pairs of connecting links may be connected to the outer ends of the pawl carrying arms so set, while at the other end they may be connected to the end of a single pivoted arm.

It will, however, be understood that the construction hereinbefore described or some other construction of duplicate operating mechanism is preferred.

Again, instead of providing the cam mechanism hereinbefore described any other operating mechanism may be employed according to the design or construction of press to which the invention is to be applied.

In the modified construction represented in Figures 3 and 4 of the accompanying drawings, the cam levers q, r are provided as simple upstanding levers pivoted at their lower ends and carrying at the upper ends runners q^1, r^1 for engagement with cams (not shown) carried upon a transversely disposed cam shaft s . The pivot pins of the runners serve to engage the slots g^4, h^4 of the slotted arms g^3, h^3 , being advantageously provided with runners or suitable bearing surfaces for the purpose. By such a construction the cam levers are simplified in form, and the necessity for the use of bevel gear for the driving of the cam shaft is avoided. The mechanism is otherwise the same as that illustrated in Figures 1 and 2 excepting for the particular disposition of the ratchet wheels in relation to the ink fountain and small inking drum.

We claim:

Inking mechanism for printing machines, comprising an ink fountain, a fountain roller within said ink fountain, a rotating ink drum to pick up ink from said fountain roller, and mechanism to rotate said fountain roller from the drive of the machine but independently of the speed of the machine, comprising a pair of levers mounted upon a fixed pivot, a rotatable element driven from the drive of the machine and serving to oscillate the two levers alternately, a slideway formed upon the machine frame in a direction pass-

ing through the pivotal axis of the said levers, a bearing block in the said slideway, means for adjusting said bearing block along the slideway towards and away from the pivotal axis of the levers, a spindle mounted in the said bearing block, a pair of levers pivoted upon the said spindle, means upon the first pair of levers for respectively engaging said second pair of levers whereby
5 adjustment of the position of the spindle adjusts the position of said means of engagement in position upon said second pair of levers, links pivotally connected respectively to the free ends of the second pair of levers,
10 15 pawl-carrying arms connected to the said links and mounted to be oscillated on movement of the said links, pawls carried by the said pawl-carrying arms, and ratchet wheels co-axial with said pawl-carrying arms
20 and engaged by said pawls, the said ratchet wheels transmitting rotation to the fountain roller.

EDGAR WILTON SMITH.
